John L. Morris
Attorney

UNITED STATES PATENT OFFICE.

LOUIS MAXWELL PARDY, OF SOUTHAMPTON, ENGLAND.

MUTE FOR VIOLINS AND LIKE MUSICAL INSTRUMENTS.

Application filed June 1, 1925, Serial No. 34,214, and in Great Britain June 5, 1924.

My invention relates to improvements in muting devices for violins, violoncellos and similar stringed musical instruments, in which means are provided for carrying or holding the device on the instrument so as to be ready for use when required.

The objects of the present invention are to facilitate the fixing of the muting device to the instrument, and the muting and 10 muting of the strings in an efficient manner.

According to my invention, the muting body is of disk-like form eccentrically pivoted to act, in the manner of a cam, on a carrier adapted to grip the strings of the 15 instrument, the said body being firmly but rotatably and frictionally held in said carrier, with its axis parallel to the bridge of the instrument, and having a finger or like means for turning it into and out of muting 20 contact with the bridge by a finger of the bowing hand. The muting body bears against the tail-piece side of the bridge, and it may have a tangentially arranged finger to pass over the bridge and thereby 25 grip the latter between the said body and said tangential finger so as to prevent displacement of the bridge in light instruments.

A movement of about ninety degrees of the 30 muting body brings it into or out of contact with the bridge.

In the accompanying drawings, which show one suitable form of construction of a violin mute made according to my invention, Figure 1 is a view partly in section 35 and partly in side elevation, and Figure 2 is a plan view of a mute approximately one and a half times full size. Figure 2^a is a bottom view of the mute, the parts being shown in the same position as in Figure 1. Figures 3 and 4, are respectively, a plan and elevation of an approximately full sized violin mute attached to the strings, the device being in its unmuted or free position. Figure 5 is a side elevation of the device 45 attached to the violin strings and in its muted position.

Referring to the drawings, a carrier 1 is formed with a base or palm 2 and upwardly extending spaced cheeks 13, between which 50 the disk-like muting body 3 is rotatably and eccentrically mounted. Secured to the palm 2 is an upwardly projecting screw-threaded stud 4 which extends through an opening in a complementary plate or palm 5. The plate 55 or palm 5 can be screwed down into clamping association with the palm 2 by means

of the milled nut 6 which is rotatably secured in the palm plate 5 and mounted on the screw-threaded stud 4, as shown in Figure 1. The two centre strings 7, 8 of a 60 violin are clamped between the plates or palms 2 and 5 as shown in Figures 3, 4 and 5, there being no necessity to remove the strings when securing the device thereto. A part of the periphery of the muting body 65 3 is cut away as at 9 so that said body is well clear of the bridge 10 when in the off position, and a finger or spring clip 11 is suitably attached to the muting body and extends tangentially to the periphery of said 70 body adjacent one end of said cutaway portion, between which clip 11 and the periphery of the mute body 3 the bridge 10 is gripped. The clip 11 also forms a guide for the bridge when the mute body 3 is moved 75 into active position as shown in Figure 5.

The mute body 3 has a projecting part 12, preferably forming part of the spring clip 11, to serve as a finger piece for easily and quickly moving the mute body into and out 80 of engagement with the bridge by a finger of the bowing hand, there being no necessity to remove the hand from the bow in so moving the mute body.

The disk-like cheek 13 on each side of the 85 carrier 1 affords good surface support and frictional rigidity to the muting body 3. One of the cheeks 13 has a projection 14 which is engaged by a member carried by the mute 3, shown in the drawings as the 90 inner end of the clip 11, and this forms a stop for the mute 3 when in its off position.

For large sizes of mutes say for 'cellos, the 95 operating projection 12 may be formed integrally with the muting body 3. The tangential clip 11 may be dispensed with in the case of mutes for 'cellos and like instruments where the bridge is sufficiently rigid itself for the muting body 3 to be moved directly into contact with it without the 100 necessity of a guide or support.

The hereinbefore described mute can be 105 used in the ordinary way if for any reason it should be so desired, by keeping the attachment in an upturned position.

I claim:

1. A muting device for a stringed musical instrument having a bridge, said device comprising a pair of opposed members, means for rigidly clamping said members together 110 against the portions of the strings of an instrument which extend between the bridge

and the tail of the instrument, and an eccentric pivoted on one of said members on an axis adapted to lie parallel to the bridge of the instrument, said eccentric being rotatable into and out of engagement with that side of the bridge of the instrument which is adjacent the tail of the instrument.

2. A muting device for a stringed musical instrument having a bridge, said device comprising a plate, means for rigidly clamping said plate to the portions of the strings of an instrument which extend between the bridge and the tail of the instrument, said plate having a pair of spaced substantially parallel arms extending upwardly therefrom and one of said arms having a stop, an eccentric rotatable between said arms into and out of engagement with that side of the bridge of the instrument which is adjacent the tail of the instrument, and means carried by said eccentric and engageable with said stop for limiting the rotation of said eccentric when moved out of engagement with said bridge.
- 10 15 20 25
3. A muting device for a stringed musical

instrument having a bridge, said device comprising a plate, means for rigidly clamping said plate to the portions of the strings of the instrument which extend between the bridge and the tail of the instrument, said plate having a pair of spaced arms extending upwardly therefrom, a member having a cam face mounted to rotate between said arms, and a clip extending tangentially of the high part of the cam face of said member, said cam face and said clip being simultaneously movable into and out of engagement with the side of the bridge adjacent the tail of the instrument and the opposite side of said bridge, respectively.

4. A muting device according to claim 3 wherein the clip has a finger-piece extending therefrom.

5. A muting device according to claim 3 wherein one of the spaced arms has a shoulder and the clip has a portion engageable with said shoulder for limiting the rotation of the rotatable member in one direction.

LOUIS MAXWELL PARDY.
